(57) **CLAIM**

The ornamental design for headset, substantially as shown and described.

DESCRIPTION

FIG. 1 is a perspective view of a headset having two ear cups as seen from the front and left side, the cord is drawn broken away for indeterminate length;

FIG. 2 is a perspective view thereof as seen from the front and right side

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

FIGS. 1-8 show a headset with one ear cup and a boom microphone on the right. The dotted line portions of the drawings represent environmental structure only and do not form part of the claimed design.
